UNITED STATES PATENT OFFICE.

ANDRZEJ ORZECHOWSKI, OF KANE, PENNSYLVANIA.

MOCCASIN.

No. 850,961.

Specification of Letters Patent.

Patented April 23, 1907.

Application filed June 20, 1906. Serial No. 322,578.

To all whom it may concern:

Be it known that I, ANDRZEJ ORZECHOWSKI, a subject of the Emperor of Austria, residing at Kane, in the county of McKean and 5 State of Pennsylvania, have invented certain new and useful Improvements in Moccasins, of which the following is a specification, reference being had therein to the accompanying drawings.

10 My invention relates to footwear, and more particularly to that class known as "moccasins," one of the objects being to provide a moccasin that shall be simple and inexpensive in construction, durable, adjustable to conform to feet of different sizes and shapes, and neat and attractive in appearance, and which can be constructed out of a single piece of material.

Other objects and advantages of my invention, as well as the structural features by 20 means of which they are attained, will be made clear by an examination of the specification, taken in connection with the accompanying drawings, in which the same reference-numerals indicate corresponding portions throughout, and in which—

Figure 1 is a perspective view of a moccasin made in accordance with this invention, and Fig. 2 is a bottom plan of the strip of 30 material cut ready to be shaped into position and sewed. Fig. 3 is a rear view of the moccasin shown in Fig. 1.

1 designates a piece of material which forms the sole and upper and is preferably of 35 soft and yielding leather having its rear edge cut to form two V-shaped recesses 2, separated by a projecting point or tongue 3. The front edge of the strip is also cut to form two V-shaped recesses 4, separated by a projecting point or tongue 5. The outer walls 40 of the V-shaped recesses 2 are rounded instead of straight, as shown at 6, while the outer walls of the V-shaped recesses 4 are approximately straight, as at 7. The corners of the front edge are brought together, the point or tongue turned upward, as shown in Fig. 1, and the whole stitched together. The corners of the rear edge are likewise brought together and the tongue 3 turned up, as 45 in Fig. 3, and the whole stitched together, as shown. The leather or material is cut in the shape and manner shown in order that all parts may meet evenly when brought together and stitched or sewed and to give 50 rounded effects to the toe and heel.

55 8 designates straps or lacings, which are

formed integral with the strip 1 and cut from its sides, as shown. Each outer edge of the strip 1 is also cut somewhat waving, leaving depressions 9 in said edges, the purpose of 60 which will hereinafter more clearly appear. The sides of said strip near its edges are provided with a longitudinal row of slits 10, through which slits the straps or lacings 8 pass in interwoven or interlaced manner, as 65 shown in Fig. 1, the ends being then brought back, so that the straps or laces on each side of the moccasin engage a hook 11, carried by the eyelet 12, secured in the edge of the moccasin, and then pass over the foot in advance 70 of the instep and are tied or held in place by a buckle, as desired.

A preferred form of lacing the moccasin is shown in Fig. 1, although it is obvious that other modes may be resorted to, according to 75 the ideas of the wearer. In the form shown the straps or lacings 8 pass through a predetermined number of the slits until the straps or laces reach the depressions 9. They are then turned over the edges, as at 80 13, and enter the next slit from the inside of the moccasin. If preferred, the ends may be extended to the last slit and then tied around the ankle or brought to meet behind the foot and there connected.

85 It will at once be obvious that various modes of securing the moccasin to the foot by means of the novel construction thereof and the arrangement of parts as shown and described will suggest themselves to the wearer, 90 and it is thought from the foregoing description the objects, advantages, and purposes of the invention are made clear and that further explanation is not necessary.

Having thus described my said invention, 95 what I claim as new, and desire to secure by Letters Patent of the United States, is—

1. A moccasin comprising a single piece of material having a row of slits extending longitudinally thereof on each side near the edge, said piece being cut to form V-shaped recesses at the front and rear edges, said recesses being divided by a lateral point or tongue, the rear corners brought together and the edges united with the tongue and 100 with each other, and the front corners being also brought together and the edges united with the tongue and with each other, and straps or laces formed integral with the piece of material and laced or interwoven in the 105 slits.
2. A moccasin comprising a single piece of

- material having a row of slits extending longitudinally thereof on each side near the edge, said piece being cut to form V-shaped recesses at the front and rear edges, said recesses being divided by a lateral point or tongue, the rear corners brought together and the edges united with the tongue and with each other, and the front corners being also brought together and the edges united with the tongue and with each other, and straps or laces formed integral with the material and passed through the slits on either side, thence brought back and united in advance of the instep.
3. A moccasin comprising a single piece of material having a row of slits extending longitudinally thereof on each side near the edge, said piece being cut to form V-shaped recesses at the front and rear edges, said recesses being divided by a lateral point or tongue, the rear corners brought together and the edges united with the tongue and with each other, and the front corners being also brought together and the edges united with the tongue and with each other, straps or laces formed integral with the material and passed through the slits on either side, thence brought back and united in advance of the instep.
4. A moccasin comprising a single piece of material cut to form V-shaped recesses at the front and rear ends, the outer walls of the rear recesses being rounded and said recesses being separated by a projecting point or tongue, the rear corners united and the edges united with the tongue and with each other, the front corners being also united and the edges united with the tongue and with each other, a hook mounted on each side of the upper formed by the edges of the material, and straps or laces formed integral with the material and adapted to be interwoven or interlaced through slits cut in the edges of the material and also engaging the hook whereby they are held in position.

brought back and united in advance of the instep, and a combined hook and eyelet secured to each upper edge of the moccasin and 30 adapted to be engaged by the straps or laces.

4. A moccasin comprising a single piece of material cut to form V-shaped recesses at the front and rear ends, the outer walls of the rear recesses being rounded and said recesses 35 being separated by a projecting point or tongue, the rear corners united and the edges united with the tongue and with each other, the front corners being also united and the edges united with the tongue and with each 40 other, a hook mounted on each side of the upper formed by the edges of the material, and straps or laces formed integral with the material and adapted to be interwoven or interlaced through slits cut in the edges of 45 the material and also engaging the hook whereby they are held in position.

In testimony whereof I hercunto affix my signature in presence of two witnesses.

ANDRZEJ ORZECHOWSKI.
